[57] **ABSTRACT**

The invention relates to an arrangement for accelerating, to a predetermined velocity at least one bunch from a bunched beam of particles, the length of said bunch corresponding to one cycle of the high frequency of the accelerator.

In this arrangement the injection voltage V of the beam is raised to a value larger than the cut-off voltage V_c of the accelerator, exclusively during a short period. Said injection voltage V is created by the addition of a pulsed voltage V_o and high-frequency voltages V_1 and V_2 generated in resonant cavities 3 and 4 disposed in the trajectory of the beam and tuned respectively to a sub-multiple of said high frequency.

PARTICLE PREACCELERATOR ARRANGEMENT

The present invention relates to linear particle accelerators. In these kind of equipment, a particle beam passes through a linear structure formed by a linear arrangement of resonant cavities containing openings for the passage of the beam and supplied from a high-frequency power source. It is well known that these particles are, during their displacement, progressively regrouped into bunches which succeed one another at the output of the accelerator, at the frequency of said power source.

However, in certain applications, it may be desirable to accelerate only one bunch or package of particles, for example in order to simulate a single nuclear event or to study the very short lifetime of metastable chemical elements. This requirement means that the length of the package corresponds at the most to one cycle of the high acceleration frequency. Several solutions have already been proposed for this problem.

Thus the operation of a linear particle accelerator being generally of a pulsed nature, the pulse duration may be reduced down to a value corresponding to only one cycle of the high acceleration frequency; however, this becomes hardly feasible as soon as the accelerating frequency exceeds 100 Mc/s, value which is a rather low value indeed.

Another solution consists in subjecting the beam to transverse deflection, either electrical or magnetic, so that it can only enter the linear accelerator structure during the brief instants when there is no deflection.

However, this may substantially affect the geometric and energetic characteristics of the beam.

It is an object of this invention to avoid such drawbacks to this effect, the particles outside the useful bunch being completely eliminated.

On the other hand, in the device of the invention, the accelerated particle bunch is that at the peak of the HF wave which, at this instant, has a zero transverse component; therefore there is no undesired defocusing of the beam.

According to the invention, there is provided a buncher and preaccelerator arrangement for preaccelerating to a predetermined velocity, particle bunches intended to be injected into the accelerating sections of a particle accelerator, said arrangement comprising: a particle source; means for extracting said particle from said source; a first cavity resonator and at least one second cavity resonator positioned along the path of said particles, cavity resonators being provided with respective openings for the propagation of said particles therethrough; means for applying an electromagnetic energy at the high frequency f_1 to said first cavity resonator for bunching said particles therein; and means for applying an electromagnetic energy at the high frequency f_2 to said second cavity resonator for preaccelerating one bunch at a time at predetermined time intervals; said high-frequencies f_1 and f_2 being sub-multiples of the operating frequency f_o of said accelerator, and said frequencies f_1 and f_2 being harmonically related.

In a better understanding of the invention and show how the same may be carried into effect, reference will be made to the following description and the appended drawings among which:

FIG. 1 illustrates an arrangement according to the present invention;

FIGS. 2 to 4 are explanatory diagrams of this arrangement.

The arrangement shown in FIG. 1 comprises a sound 1 emitting an electron beam 2, a first resonant cavity 3 and a second cavity 4. They are traversed at 5 and 6 by the beam 2 which enters the first section of a linear accelerator 10 of any known type which, therefore, has not been illustrated in detail. The positive pole 9 of a pulsed voltage source 7 is connected to the cavities 3 and 4, whereas the negative pole 8 thereof is connected to the cathode.

The accelerator is operating at the high frequency and the high frequency power is issued from a klystron tube 13 through the line 14.

15 This klystron operating at the frequency f_o is supplied from a pulsed voltage generator 30 having a recurrence frequency equal to 7. The resonant cavities 3 and 4 are respectively supplied with high frequency signals of frequency $f_1 = F_o/10$ and $f_2 = f_o/2$ through the lines 11 and 20 12, the reason for this choice being explained hereinafter. The master oscillator is a high stability generator 15 producing a low-power high-frequency output of frequency f_1 .

One part of this low-power high-frequency energy 25 which is amplified by an amplifier 16, is applied to the cavity 3 after conventional level and phase adjustment in a variable attenuator 17 and a phase shifter 27 respectively, whereas the other part of this energy is applied to a frequency multiplier 18 which multiplies the 30 frequency by 5.

One part of the energy issued from said multiplier 18, and amplified in the amplifier 19, is applied to the cavity 4, the other part of the energy being injected into a multiplier 21 which multiplies its frequency by 2. The 35 energy issued from said multiplier 21 is then applied to amplifier klystron 13, through a phase shifter 23 and a variable attenuator 22.

The instant at which the voltage pulse produced by the pulse generator 7 is triggered, is determined by the 40 application to said generator 7 of a synchronising signal, adjusted by a phase-shifter 25 and produced by the synchroniser 26 in accordance with the phase of the high-frequency signal coming from the master oscillator 15.

45 Thus, the cavity 3, the cavity 4 and the klystron 13 are continuously supplied with high-frequency power, of frequency respectively equal to $F_o/10$, $f_o/2$ and f_o . The klystron 13 fed by the voltage generator 30 at an arbitrary recurrence frequency F is operating at high-frequency f_o equal to the high-frequency of the particle accelerator 10 and supplies it.

The operation of this kind of system, which is described in order to simplify matters in relation to the case in which it is desired to accelerate a single bunch of electrons through the accelerator, is as follows:

The pulse generator 7 produces a single voltage pulse of amplitude V_0 and duration $10 T_0$, this being equal to one cycle of the frequency $f_o/10$ produced by the master generator 15. This voltage determines the emission, by the cathode of electrons which are injected into the cavity 3 at a velocity corresponding to the voltage V_0 . Into the first cavity 3, the electrons experience an increase in velocity corresponding to the high frequency voltage V_1 which prevails in the drift space 5 of cavity 60 3. These electrons are then bunched in bunches.

In the second cavity 4, one of these bunches experiences a fresh increase in velocity corresponding to the

high-frequency voltage V_2 which prevails in the drift space 6 of said cavity. The final velocity of said bunch of electrons is determined by the sum V of the three voltages $V_0 + V_1 + V_2$. However, the theory of operation of a particle accelerator shows that there is a value of the injection voltage below which the velocity of the particles is too low for any of them to be "captured" by the effective accelerating wave in the accelerator 10, and above which the current supplied by accelerated particles increases rapidly with the injection voltage. This particular voltage will, throughout the following, be called the "cut-off" voltage V_c .

FIG. 2 illustrates this fact by means a diagram on which the accelerated current I corresponding to a typical accelerator has been plotted versus the injection voltage V comprised between O and V_c . As shown, the accelerated current I increases rapidly.

Thus the respective adjustment of the three values V_0 , V_1 and V_2 makes it possible to exceed the value V_c in all cases and to achieve the capture of particles by the accelerating wave, i.e., the acceleration thereof. However, to obtain the electron package having a length corresponding to one cycle at the high frequency, the device shown in FIG. 1 requires special control. This will be shown with particular reference to FIG. 3.

FIG. 3 illustrates the variations (plotted on the ordinates) in the voltages V_0 , V_1 , V_2 referred to hereinbefore as a function of time.

The voltage V_0 is adjusted to a value much lower than the cut-off voltage V_c ; it is added to it the alternating voltage V_1 of frequency $f_0/10$ which is set to a value such that the sum $V_0 + V_1$ is equal to V_c .

The alternating voltage V_2 of frequency $f_0/2$ is alone to cause the voltage V_c to be exceeded, and consequently brings about the acceleration of an electron bunch.

This bunch is very narrow. Its length corresponds to that of an arc 40 of the sinusoidal signal of frequency $f_0/2$ as shown in FIG. 3, the length of this arc being consequently equal to the length of a complete oscillation 42 at the high frequency f_0 .

It should be noted that the three voltages V_0 , V_1 and V_2 should exhibit their instantaneous peak values simultaneously, and this is why the phase-adjusting devices described in FIG. 1 are needed. It should be noted, too, that it is necessary, in order to obtain a single electron bunch, that only one arc 40 of the sinusoidal voltage V_2 of frequency $f_0/2$ should exceed the value $V_c = V_0 + V_1$ which requires, in practice, that the frequencies of the high-frequency signals applied respectively to cavities and klystron tube should be chosen as indicated hereinbefore, and in particular, explains the choice of an odd number for the ratio between the frequencies of the two cavities.

However, other values of these factors can be resorted to without departing from the scope of the invention, at the expense however of the production of parasitic electron bunches or of a package of greater length.

FIG. 4 illustrates the variations in current produced over the length of the accelerated electron bunch. The value of the accelerated current I is depending on the accelerating voltage V_2 of the beam. The length of the current pulse 41 emitted by the electron gun, extends over a period equal to $10 T_0$, corresponding to the fre-

quency $f_0/10$; a pulse of this kind can be produced in a known manner.

However, the length of the accelerated electron bunch extends over only a period T_0 corresponding to the high frequency f_0 ; but a high-current pulse of this kind cannot be obtained in the prior art devices, as already stated.

By way of example, it may be indicated that for an accelerating high frequency wave of 1300Mc/s, the voltages $V_0 = 50$ kV, $V_1 = 30$ kV, $V_2 = 40$ kV can be used. The value of the voltage V_0 applied to the cathode, is a much lower value than the 140 KV required in the case of conventional electron guns.

This advantage in terms of voltage values, may be accompanied by a further advantage which is concerned with the characteristics of the accelerated pulse.

Thus, either by slightly detuning the cavities or changing slightly their relative phase, it is possible to modify the time dependance law of the velocity modulation applied to particles, so that, after traversing an appropriate length of field free drift space, the bunching of the particles and therefore the density of the bunches formed are improved. If, subsequently the beam is passing through a conventional "premodulating cavity," which is either a separate one or is integral part of the accelerating structure, said cavity being fed at the nominal frequency of the latter, this conventional premodulating cavity gives a time-compression effect, in the current pulse produced by the electron gun, arrangement without any particle loss and consequently there results an improvement in the peak value of current delivered by the accelerator.

The embodiment of the invention as described hereinbefore is given purely by way of a non-limitative example.

In particular, the means used to create the high-frequency signals applied to the different elements of the device can differ from those described, the order of the resonant cavities can be reversed and their number be in excess of two; the pulse-operated electron gun, which is of the diode type in the description, may be of the triode type, supply by a direct voltage applied between cathode and anode, beam injection being controlled by a grid; finally, the accelerated particles can be either electrons or ions.

What is claimed is :

1. A buncher and preaccelerator arrangement for preaccelerating, to a predetermined velocity, particle bunches intended to be injected into the accelerating sections of a particle accelerator, said arrangement comprising : a particle source ; means for extracting said particles from said source ; a first cavity resonator and at least one second cavity resonator positioned along the path of said particles, said cavity resonators being provided with respective openings for the propagation of said particles through said cavity resonators ; means for applying an electromagnetic energy at the high-frequency f_1 to said first cavity resonator for bunching said particles therein ; and means for applying an electromagnetic energy at the high-frequency f_2 to said second cavity resonator for preaccelerating one bunch at a time at predetermined time intervals ; said high-frequencies f_1 and f_2 being submultiples of the operating frequency f_0 of said accelerator, and said frequencies f_1 and f_2 being harmonically related.
2. An arrangement as claimed in claim 1, wherein said first and second cavity resonators are adjacent and

respectively tuned to frequencies f_1 and f_2 , one of said submultiple frequencies f_1 and f_2 being an odd multiple of the other.

3. An arrangement as claimed in claim 2, wherein said submultiple frequencies f_1 and f_2 are respectively one-half and one-tenth of said frequency f_0 .

4. An arrangement as claimed in claim 1, wherein said means for extracting said particles are a D.C. voltage supply.

5. An arrangement as claimed in claim 4, wherein said second cavity resonator is so dimensioned that the sum of the peak values of said supply voltage and of the

high frequency voltage V_1 corresponding to said energy at high frequency f_1 applied to said first cavity resonator is at least equal to the cut-off voltage V_C of said accelerator.

5 6. An arrangement as claimed in claim 1, wherein said particles are electrons.

7. An arrangement as claimed in claim 1, wherein said particles are ions.

10 8. A particle accelerator comprising a preaccelerating arrangement as claimed in claim 1.
